[57] CLAIM

The ornamental design for a bouquet holder, as shown and described.

DESCRIPTION

FIG. 1 is a perspective view of a bouquet holder showing my new design;

FIG. 2 is a front view thereof;

FIG. 3 is a right side view thereof, the left side being a mirror image;

FIG. 4 is a rear view thereof.

The cross-line shading which is partially shown on the collar and handle is understood to repeat uniformly across the circumscribed area and to represent conventional fabric.
